CLAIM

The ornamental design for a drape ring, as shown and described.

DESCRIPTION

FIG. 1 is a top perspective view of a drape ring of our new design;

FIG. 2 is a bottom perspective view of the drape ring of FIG. 1;

FIG. 3 is a top plan view of the drape ring of FIG. 1;

FIG. 4 is a bottom plan view of the drape ring of FIG. 1;

FIG. 5 is a front elevation view of the drape ring of FIG. 1;

FIG. 6 is a rear elevation view of the drape ring of FIG. 1;

FIG. 7 is a left side elevation view of the drape ring of FIG. 1; and,

FIG. 8 is a right side elevation view of the drape ring of FIG. 1.

The broken lines depict portions of the drape ring and form no part of the claimed design.

1 Claim, 4 Drawing Sheets(56)
